UNITED STATES PATENT OFFICE.

HAROLD D. ALLEN, OF EAST HAMPTON, CONNECTICUT.

TOY TELEVISION.

Application filed June 2, 1927. Serial No. 196,118.

My invention relates to the class of toys simulating ordinary telephones, and an object of my invention, among others, is the production of a toy that shall simulate, in accordance with a child's idea, the recent innovation of means for seeing the person with whom one may be talking over the telephone.

One form of toy embodying my invention and in the construction and use of which the objects herein set out, as well as others, may be attained, is illustrated in the accompanying drawings, in which—

Figure 1 is a view in front elevation of a toy embodying my invention, with parts broken away to show construction.

Figure 2 is a view in side elevation.

Figure 3 is a view, scale enlarged, in section through the transmitter on a plane denoted by the dotted line 3—3 of Figure 1.

Figure 4 is a similar view, scale enlarged, on a plane denoted by the dotted line 4—4 of Figure 2.

Figure 5 is a detail view showing the arrangement of the dial in the base of the telephone.

While the device embodying this invention is simply a toy, and, therefore, not capable of actual service, or function of an actual set, yet, in order to simplify the description the same terms are used herein as are applied to parts simulating like comparing parts in a regular telephone set.

In the accompanying drawings the numeral 5 indicates the base of my improved telephone, 6 a post or standard rising therefrom, 7 a bell secured at the side of the post or standard, 8 a receiver adapted to be suspended on a hook 9 pivotally mounted at one end within the bell 7 and adapted to ring the latter by movement of the hook up-and-down. The numeral 10 indicates a cord connected to the receiver. All of the parts thus far described are of old and well known construction in toys of a similar character, and except in connection with other parts hereinafter described, do not constitute the invention of this application.

A support 11 extends upwardly from the end of the post or standard 6 and a transmitter bar 12 is pivotally attached to the support, as shown in Fig. 2 of the drawings. A transmitter is secured to the bar 12, this transmitter comprising a shell 13, perforated to receive said bar, a cover 14, a display plate 15, a face plate 16 and a mouth piece 17,

this transmitter as whole being formed to represent the transmitter of an ordinary telephone.

In embodying my idea in the structure the display plate and face plate are relatively movable for the purpose of locating a display opening 18 on the face plate opposite pictures 19 on the display plate and also for locating an index 20 and names or similar designations 21 on the display plate to register respectively with indicating characters 22 and an opening 23 on the face plate.

In the preferred form and as shown herein the display plate is rotatably mounted upon a pivot formed by clips 24 cut from an opening in the center of the face plate and backturned as shown in Figure 4 of the drawings.

The bar 12 extends through holes made in the cover, display plate, face plate, and in the bottom of the mouth piece 17, and is headed over as at 25 at the bottom of the mouth piece to secure said plates together, but loose enough to permit rotation of the display plate 15. As a means for rotating the display plate a tab 26 is provided extending from the periphery of said plate and upon which the index 20 may be displayed.

The operation of the device will be readily understood, a child wishing to call its pal the tab 26 is moved to register the index 20 with the word "Pal" on the face plate 16, and this causes the word Pal to appear at the opening 23 and the picture through the opening 18. It will thus be seen that the device has an educational as well as an amusement value as a child will not only learn the relationship of pictures and characters, but it will also learn to read the words appearing upon the face plate and to associate such words with the characters represented by them.

The different parts of the toy may be made of any suitable material as may be desired, and the discs or plates 15 and 16 may be composed of paper, celluloid, or any other suitable material.

While the invention is illustrated in the drawings herein as applied in connection with the transmitter it is obvious that the same idea may be carried out by locating the display or "television" device on parts other than the mouth piece of the instrument.

2
In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A toy telephone comprising a telephone structure including a part simulating a transmitter and a part simulating a receiver, both permanently secured to said structure a display plate having representations of different persons or things which will appeal to a child as desirable objects of telephone communication depicted thereon, means for separately displaying said representations, and means for indicating the position of the representations with respect to the means for displaying them.
2. A toy telephone including a part simulating a transmitter and a part simulating a receiver, said transmitter including a display plate having representations of different persons or things which will appeal to a child as desirable objects of telephone communication depicted thereon, and means for displaying said representations, said plate and displaying means being relatively movable for separate display of said representations.
3. A toy telephone including a part simulating a transmitter and a part simulating a receiver, said transmitter including a rotatably mounted display plate having representations of different persons or things which will appeal to a child as desirable objects of telephone communication depicted thereon, and a plate having openings through which said representations are displayed.
4. A toy telephone including a part simulating a transmitter and a part simulating a receiver, said transmitter including a face plate having openings, a display plate rotatably mounted back of the face plate and having representations of different persons or things which will appeal to a child as desirable objects of telephone communication depicted thereon, and means on said face plate and display plate for determining the position of each of said representations.
5. A toy telephone including a part simulating a transmitter and a part simulating a receiver, said transmitter including a face plate having an opening with clips formed from metal bent out of said opening, said face plate also having a display opening, and a display plate rotatably mounted on said clips and having characters located thereon for display through said display opening in the face plate.

6. A toy intended to simulate a telephone of the "television" type including a telephone structure having a transmitter and a receiver, means permanently secured to said telephone structure and having a fixed "vision" space formed thereon, and means for selectively displaying through the said "vision" space representations of different persons or things which will appeal to a child as desirable objects of telephone communication. 75

7. A toy intended to simulate a telephone of the "television" type including a telephone structure having a transmitter and a receiver, means permanently secured to said telephone structure and having a fixed "vision" space formed thereon, and a plate movably mounted with respect to the aforesaid space for selectively displaying through the latter representations of different persons or things which will appeal to a child as desirable objects of telephone communication. 80

8. A toy intended to simulate a telephone of the "television" type including a telephone structure having a transmitter and a receiver, a cover plate permanently secured to said telephone structure and having a fixed "vision" window formed therein, and means for selectively displaying through said "vision" window representations of different persons or things which will appeal to a child as desirable objects of telephone communication. 85

9. A toy intended to simulate a telephone of the "television" type including a telephone structure having a standard, a transmitter, a receiver, and independent means for supporting said transmitter and receiver upon said standard, means permanently secured to the standard by the supporting means for said transmitter and having a fixed "vision" space formed thereon, and means for selectively displaying through said "vision" space representations of different persons or things which will appeal to a child as desirable objects of telephone communication. 100

10. A toy intended to simulate a telephone of the "television" type including a telephone structure having a standard, a transmitter, a receiver, and independent means for supporting said transmitter and receiver upon said standard, a cover plate permanently secured to said transmitter by the supporting means for the latter and having a fixed "vision" window formed therein, and means for selectively displaying through said "vision" window representations of different persons or things which will appeal to a child as desirable objects of telephone communication. 115
